RAIL CROPPING MACHINE

James L. Anderson, Closter, N. J., assignor to Air Reduction Company, Incorporated, New York, N. Y., a corporation of New York

Application January 10, 1941, Serial No. 373,920

26 Claims. (Cl. 266—23)

This invention relates to cutting machines, and more particularly to machines for cutting off the battered ends of rail.

It is an object of this invention to provide an improved cutting machine, and one suitable for cropping the ends of rails. Another object is to produce with gas torches cuts that are right sections through the rail, or that leave the new end face of the rail concave so that the rails from which ends have been cut can be positioned with the ball and flange of one rail close to the ball and flange of another.

Another feature of the invention relates to the automatic positioning of the torches when control mechanism is actuated to start a cutting operation, and still another feature relates to automatic control of the torches in their cutting operations. Certain of the control mechanism are applicable to cutting machines generally. It may be said, therefore, that another object of the invention is to provide improved automatic control means for a torch cutting machine.

While this invention will be described as embodied in a rail cropping machine, the apparatus can be used for other cuts, and in addition to the controls some other features of the invention can be employed on cutting machines used for various purposes.

Other objects, features and advantages of the invention will appear or be pointed out as the specification proceeds.

In the accompanying drawings, forming part hereof:

Fig. 1 is a side elevation of a cutting machine embodying the invention.

Fig. 2 is an enlarged top plan view, partly in section, of the machine shown in Fig. 1.

Fig. 3 is an end view, partly in section and partly broken away, of the machine shown in Fig. 2.

Figs. 4^a and 4^b are diagrammatic views, which, when combined, show the electric circuits and control apparatus of the cutting machine illustrated in the other views, and with the relative positions of most of the parts similar to those of Fig. 1.

Fig. 5 is an enlarged sectional view of one of the solenoid-actuated valves.

The embodiment of the invention shown in the drawings includes a stationary frame 5 with a base 6 which rests on the floor or other support. The stationary frame 5 includes two upright guide portions 7 connected by a web 8. Movable frames 9 and 10 have bearing guideways

11 (Fig. 2) which fit around flanges 11' on the upright guide portions 7 so that the frames are vertically movable along the guide portions 7. These two frames 9 and 10 (Fig. 1) are of similar construction in order to standardize manufacture of the parts, but in the use of the machine the lower frame 9 rests on the base 6 and is not moved. All adjustment of the spacing of these frames is effected by raising or lowering the upper frame 10. An upper torch support or slide 12 slides in horizontal guides 13 and 14 on the frame 10. A lower torch support or slide 16 slides in similar guides 17 and 18 on the frame 9.

At one end of the upper slide 12 there is a cross slide 22 with guides 23 in which a bracket 24 slides horizontally, and at right angles to the direction of movement of the slide 12. The bracket 24 is moved along the guides 23, and held in any set position lengthwise of these guides, by a lead screw 25 in a manner well understood in the art.

A torch 27 is carried in a torch holder 28, and this torch holder is swivelly connected to the bracket 24 by a pivot screw 29. The torch 27 is adjustable up and down in the torch holder 28 by rack and pinion adjustment mechanism actuated by a knob 31.

There are two solenoids 33, best shown in Fig. 2, attached to the upper end of the bracket 24. An armature 34 extends through both solenoids 33 and has its travel in both directions limited by screws 35 threaded through the bracket 24 at the outer ends of the solenoids. These screws are held in position by lock nuts 36.

The upper end of the torch holder 28 forms a yoke 37 which is connected with the armature 34 so that movement of the armature under the pull of one or the other of the solenoids 33 rocks the torch holder 28 on its pivot 29 (Fig. 1) and tilts the torch 27 into a slightly inclined position to either side of the vertical. The inclination is of the order of one degree.

The purpose of this slight inclination of the cutting torch is to obtain a straight or somewhat undercut face on the end of a rail 38 or other work-piece which the torch is used to cut. The cut made with an oxygen torch, under the operating conditions of the invention, is slightly wider at the top than at the bottom. With a vertical oxygen stream, this means that both faces of the cut have a slight slope.

By inclining the torch slightly, the slope on one face of the cut is increased, and the other side can be made vertical or slightly undercut. The torch 27 is inclined so as to produce the

sloping face on the crop end of the rail, thus leaving the new end face of the rail in condition to abut against the end of another rail with the heads of the rails in contact. The slope of the torch must be in opposite directions when cutting the opposite ends of the rail in order to have the sloping face on the crop end in both cases. The torch can be inclined in either direction by exciting one or the other of the solenoids 33.

A lower torch 40 is carried by a torch holder 41 and is adjustable vertically in the torch holder by a knob 42 that operates well-known rack and pinion mechanism. The torch holder 41 is swivelly connected by a pivot screw 44 to the end of the slide 16. The torch holder 41 can be rocked about the pivot 44 by solenoids 45 in the same way that the upper torch holder 27 is rocked on its pivot screw 29, already described.

There is no provision for adjusting the lower torch 40 horizontally at right angles to the direction of movement of the slide 16. No such adjustment is necessary because the upper torch 27 can be adjusted lengthwise of the rail to bring it into position to cut in the same plane as the lower torch 40.

The slides 12 and 16 are moved back and forth in the guides 13, 14, and 17, 18, respectively, by separate mechanisms each of which is driven by its own electric motor. A motor 47 supplies power to shift the slide 12, and a similar motor 48 moves the lower slide 16. Both motors are preferably equipped with centrifugal governors 49, 50, which can be set to hold the motors to a desired uniform speed.

The mechanism driven by the motors 47, 48 is best shown in Fig. 3. The motor 47 is attached to the frame 10 and drives a vertical shaft 52 through reduction gearing 53. A worm 55 is secured to a shaft 56 which is journaled in a housing 57 and connected with the vertical shaft 52 by a coupling 58.

The motor 48 is attached to the frame 9 and drives motion-transmitting connections similar to those driven by the motor 47 and indicated by the same reference characters. The lower end of the shaft 56 which drives the worm is broken away to show a worm wheel 60, the hub of which abuts against one end of a sleeve 61. The worm wheel 60 and sleeve 61 are running fits on a shaft 62 in the lower housing 57.

Just beyond the end of the sleeve 61 is a gear 64 keyed to the shaft 62. A thrust bearing 65 at the right end of the hub of the gear 64 bears against a wall of the housing 57. A hand wheel 67 is connected to the shaft 62 near one end by a spline connection that permits relative axial movement of the hand wheel 67 on the shaft 62.

A clutch nut 68 is threaded to the end of the shaft 62. Tightening this clutch nut 68 forces the hand wheel hub against a thrust bearing surface on the side of the housing 57 and draws the shaft 62 to the right in Fig. 3 so that the enlarged end 69 of the shaft 62 clamps the hub of the worm wheel 60 against the gear 64 and causes the gear and worm wheel to turn as a unit.

There is a rack 73 on the back of the slide 16. A pinion 74, secured on a shaft 75, meshes with the rack 73. The shaft 75 turns in a bearing in a wall of the housing 57. A gear 76 secured to the left end of the shaft 75 meshes with the driving gear 64.

When the clutch nut 68 is tightened the worm wheel turns the gear 64 and through it the gear 76, shaft 75, and gear 74 which moves the rack 75

73 and the slide 16 to which the rack is connected. When the clutch nut 68 is released, the worm wheel 60 turns freely on the shaft 62, but the slide 16 can be moved by turning the hand wheel 67 which will always turn the driving gear 64 because the hand wheel and gear 64 are both keyed to the shaft 62.

The movable frame 10 is raised and lowered by a jack screw 78 (Fig. 1) that threads through a central portion of the movable frame 10. The screw 78 is supported by a top casting 79 which is fastened to the upper ends of the guide portions 7 by stud bolts 80. A worm wheel 82 is secured to the upper end of the jack screw 78. A worm 83 (Fig. 2) fixed on a short shaft 84 meshes with the worm wheel 82, and the shaft 84 is rotated, to raise and lower the movable frame 10, by a hand wheel 85.

The automatic controls include switches 87 and 88 attached to the movable frame 10 of the machine. Each of the switches 87, 88 has an actuator 90 with a roller 91 that is pressed against a track 92 by spring pressure of the switch. The track 92 is rigidly attached to the slide 12. The roller 91 of switch 87 bears against the top face of the track, and the roller 91 of the switch 88 bears against the bottom face of the track. An abutment comprising a cam member 94 is adjustable along a slot in the track 92 and can be locked in any set position along the track by a clamping screw 95. A cam surface on the cam member 94 displaces the roller 91 and actuates the switch 87 whenever the cam member 94, traveling with the slide 12, moves under the switch 87.

A similar abutment or cam member 97 is clamped in position along the track 92 to actuate the switch 88. There are switches 98 and 99 attached to the lower frame 9 of the machine close to the slide 16. These switches 98 and 99 have actuators with rollers 91 that are displaced by cam members 94 and 97 that are adjustable along a track 92 in the same manner as the similarly designated parts associated with the upper slide 12 and the switches 87, 88.

There are four switch boxes 101-104 attached to the frame 9 within convenient reach of an attendant of the machine. Each of these switch boxes has two push-buttons, for manually actuating the switches within the boxes.

Figs. 4^a and 4^b show the control apparatus and circuits. The control apparatus includes five main groups of controls and a number of additional switches that are in circuits with the other controls but not physically grouped with them. The main groups include the "upper motor controls," the "lower motor controls," and the "fuel gas controls" shown in Fig. 4^a and identified by legends. The "preheating oxygen controls" and "cutting oxygen controls" are shown and labeled in Fig. 4^b.

The main control switch in the box 101 is a two-position switch and when in closed position connects a line L with a power line marked "+" in Fig. 4^a. The line L supplies power to a number of different units of the control apparatus but in order to simplify the wiring diagram the circuits from the switch box 101 are not shown connected. It is sufficient to understand that all terminals and conductors marked "L" in Figs. 4^a and 4^b are connected with the conductor L from the main switch in box 101.

The switch 88 (Fig. 4^b) is closed by its spring bias except when the slide 12 is far enough to the right to cause the roller 91 of the power cut-off

switch 88 to be displaced downward by the cam member 97 on the slide 12. When the switch 88 is closed it completes a circuit from conductor L, through a conductor 106 to solenoids 107 (Fig. 4a) of the upper motor controls. There are four solenoids 107 shown in the drawings connected with conductor 106 and each operating one of the first four switches 108 in a switch box 109 which houses the upper motor controls. Instead of these four solenoids, a single solenoid can be used with mechanical connections for causing the first four switches 108 to open and close together.

The other sides of the solenoids 107 are connected with a conductor 111 that leads to a contact 112 of switch 87. The blade 113 of switch 87 has a spring bias away from the contact 112 but when the slide 12 moves into its extreme left position and causes the roller 91 of switch 87 to be displaced upward by the cam member on slide 12, then a circuit to ground is completed from the contact 112 through the blade 113 and the solenoids 107 are energized.

The first four switches 108 in switch-box 109 are normally held open by spring bias and are closed by the pull of the solenoids 107. As soon as the first four switches 108 are closed, the solenoids 107 remain energized because a "stick" circuit to ground is established through the first switch 108, conductor 115, and other conductors of the control circuit that lead to a ground connection 116.

With the first four switches 108 closed, current flows from the line L through the second switch 108 to the armature of motor 47, and from the armature through the third switch 108, conductor 118, motor field circuit, and fourth switch 108 to the ground connection 116.

This direction of current flow causes the motor 47 to rotate in a direction to move the slide 12 to the right, but this movement of the slide 12 is not the cutting stroke and the governor 49 is not in the motor circuit. The motor runs at full speed and continues to run until the cam 97 on the slide 12 moves into position to open the switch 88.

The opening of the switch 88 breaks the power circuit to the solenoids 107 and causes the first four switches 108 to open, under the influence of their spring bias, and stop the motor 47.

The motor 47 remains stationary until power is supplied to a conductor 119 of the upper motor controls. This conductor 119 connects with the cutting oxygen controls which will be described hereinafter.

Four solenoids 121, similar to the solenoids 107, are connected on one side with the conductor 119 and on the other side to a conductor 122 which leads to a contact 123 of the switch 87. The blade 113 is held against the contact 123 by a spring bias so that unless the slide 94 on the arm 12 is in position to displace the roller 91 of switch 87, the circuit is closed from conductor 119, through solenoids 121, conductor 122, contact 123, and through switch blade 113 to ground.

When power is supplied to the conductor 119 to energize the solenoids 121, the last four (i. e. right-hand) switches 108 of the upper motor controls are closed. Power from line L flows through the eighth switch to the conductor 119 and keeps the solenoids energized after the supply of power from the cutting oxygen controls to conductor 119 is cut off. The eighth switch, therefore, controls a stick circuit for the solenoids 121.

Power from the line L also flows through the sixth switch 108 to the armature of the motor

47 and then through the fifth of the switches 108 to the governor 49 which is in series with the motor field winding. The field winding is grounded through the seventh switch 108 and a connection 116. These circuits cause the motor 47 to rotate in a direction that moves the slide 12 toward the left, and it is during this movement that the upper torch makes its cutting stroke.

When the slide 12 has moved to the left far enough for the slide member on the arm 12 to displace the roller 91 of limit switch 87 and shift the blade 113 away from contact 123 and against contact 112, the circuit through the solenoids 121 is broken, and a circuit is closed through the solenoids 107 instead, with the result that the direction of rotation of the motor 47 is automatically reversed and the slide 12 is moved back toward the right until the lower cam member on the slide 12 opens the limit switch 88 and stops the motor as previously described.

The switch 98 (Fig. 4a) is closed by its spring bias except when the lower torch supporting slide 16 is far enough to the left to cause the roller 91 of switch 98 to be displaced upward by the slide member 94 on the arm 16.

When the switch 98 is closed, it completes a circuit from conductor L, through a conductor 126 to solenoids 127 of the lower motor controls. There are four solenoids 127 and each operates one of the first four switches 128 in a switch box 129 which houses the lower motor controls. One solenoid with mechanical connections to the four switches is an equivalent of the structure indicated in the drawings.

The other sides of the solenoids 127 are connected with a conductor 131 that leads to a contact 132 of switch 99 (Fig. 4b). The blade 133 of switch 99 has a spring bias away from the contact 132, but when the lower slide 16 moves into its extreme right position and causes the roller 91 of switch 99 to be displaced downward by the slide member on arm 16, then a circuit to ground is completed from contact 132 through the blade 133 and the solenoids 127 are energized.

As soon as the solenoids 127 pull the first four switches 128 closed, against the spring bias of these switches, a stick circuit is established through the first switch 128 and a conductor 135 that connects through other parts of the control circuit with a ground connection 136.

With the first four switches 128 closed, current flows from the line L through the second switch 128 to the armature of motor 48, and from the armature through the third switch 128, conductor 138, motor field circuit, and fourth switch 128 to the ground connection 136.

This direction of current flow causes the motor 48 to rotate in a direction to move the lower slide 16 to the left. This movement is not the cutting stroke and the governor 50 is not in the motor circuit. The motor 48 runs at full speed until the slide on the arm 16 moves into position to open the switch 98.

The opening of the switch 98 breaks the power circuit to the solenoids 127 and causes the first four switches 128 to open and stop the motor 48. The motor 48 remains stationary until power is supplied to a conductor 139 of the lower motor controls. This conductor 139 connects with the cutting oxygen controls which will be described hereinafter.

Four solenoids 141, similar to the solenoids 127, are connected on one side with the conductor 139

and on the other side to a conductor 142 which leads to a contact 143 (Fig. 4b) of the switch 99. The blade 133 of the switch 99 is held against the contact 143 by a spring bias so that unless the slide member on the lower arm 16 is in position to displace the roller 91 of switch 99 downward, the circuit is closed from conductor 139, through solenoids 141, conductor 142, contact 143, and through switch blade 133 to ground.

When power is supplied to the conductor 139 to energize the solenoids 141, the last four (i. e. right-hand) switches 128 of the lower motor controls are closed. Power from line L flows through the eighth switch to the conductor 139 and keeps the solenoids energized after the supply of power from the cutting oxygen controls to conductor 139 is cut off. The eighth switch, therefore, establishes a stick circuit for the solenoids 141.

The supply of gas to the torches 27 and 40 is controlled by solenoid-operated valves that are normally held closed by their weight and spring pressure, but are opened by energizing their respective solenoids. Fuel gas, preferably acetylene, preheating oxygen, and cutting oxygen for the upper torch 27 are controlled by valves 145F, 145P, and 145C, respectively, each commanding a separate tube to the torch 27. The supply of fuel gas, preheating oxygen, and cutting oxygen for the lower torch 40 is controlled by valves 146F, 146P, and 146C, respectively. The tubes for the upper torch are indicated by the reference characters 147F, 147P, and 147C, the letters standing for fuel, preheat, and cutting gases, respectively, as in the case of the valve designations. The tubes for the lower torch 40 are similarly indicated by the reference characters 148F, 148P, and 148C.

All of the valve-operating solenoids 150 are of similar construction. The fuel gas controls are shown in Fig. 4a. There are two fuel gas control switches, an upper switch and a lower switch, in the switch box 102. There are three solenoids 151, and they receive power from the lower fuel gas control switch in switch box 102 through a conductor 153; and there are three solenoids 152, which receive power from the upper fuel gas control switch in box 102 through a conductor 154. Each of the solenoids 151 and 152 operates a separate switch 156, and these switches have a spring bias toward open position.

Each of the fuel gas control switches in box 102 is operated by a push-button and is of the momentary contact type and held open by a spring 158. When the lower switch in box 102 is closed, a circuit is completed from the power line L, through the conductor 153, solenoids 151, and conductor 142, to the contact 143 of the limit switch 99. Unless the roller 91 of limit switch 99 is pushed down (i. e. the lower torch slide 16 at the right-hand end of its stroke), there is a ground connection through the limit switch 99 and the solenoids 151 are energized.

When these solenoids 151 are energized they close the first three switches 156. The first switch 156 closes a stick circuit from the power line L to the conductor 153 so that the solenoids will remain energized after the attendant releases the button of the lower switch in box 102 and permits that switch to open.

The second switch 156 connects the power line L with one side of the solenoid 150 of valve 145F, and the other side of the solenoid 150 is grounded through the third switch 151 and a ground connection 160.

When the upper switch in box 102 is closed, 75

a circuit is established from the line L, through upper switch 102, conductor 154, the solenoids 152, and through a conductor 161 to the conductor 122 which is grounded through the limit switch 87, except when the upper torch slide 12 is at the left end of its travel and the follower 91 of limit switch 87 displaced upward. Energizing of the solenoids 152 closes the fourth, fifth and sixth switches 156. The fourth switch 156 establishes the ground connection for the solenoid 150 of valve 146F; the fifth switch 156 connects this solenoid 150 with the power line L; and the sixth switch 156 closes a stick circuit through which power is supplied to the solenoids 152 after the attendant releases the upper switch in switch box 102.

The preheating oxygen controls include two momentary contact switches in box 103 (Fig. 4b) similar to the switches in box 102 already described. These switches in box 103 supply power to the solenoids 163 that operate switches 164 which control the circuits of the solenoids 150 of the valves 145P and 146P. Since these circuits are the same as those of the fuel gas controls already described in detail, it is not necessary to repeat the description.

The cutting oxygen controls include the two momentary contact switches in the switch box 104 that are similar to the switches in boxes 102 and 103 that are connected in similar control circuits. These control circuits for the cutting oxygen supply valves 145C and 146C will be understood from the description of the fuel gas control circuits, but the cutting oxygen control switches in the switch box 104 also control the starting of the motors. A conductor 119 is connected with the cutting oxygen control circuit so as to receive power from the line L when the upper switch in the box 104 is closed, and this conductor 119 supplies power to the upper motor controls.

Another conductor 139 is connected with the cutting oxygen controls in position to receive power from the line L when the lower switch in the box 104 is closed, and this conductor 139 supplies power to the lower motor controls.

The solenoids 33 and 45, that tilt the torches 27 and 40, respectively, to produce straight or slightly concave cuts, are energized through a switch 166 that shifts the power supply first to the right-hand solenoids 33 and 45 and then to the left-hand solenoids, with alternate operations of the machine. This switch 166 includes a solenoid 167 that operates a latch 168 which rotates a ratchet 170. A rotary switch member 171, with connected contacts 180° apart, is turned through 90° by each actuation of the solenoid 167.

One side of the solenoid 167 is connected with the line L and the other side is connected, by a conductor 173, with the contact 112 of the limit switch 87. Since the blade 113 of the limit switch 87 touches the contact 112 only once during each cutting operation, the circuit through the solenoid 167 is closed only once during each cutting cycle of the machine.

The switch 166 has four fixed contacts angularly spaced by 90° and in position to be touched by the diametrically opposite contacts of the rotary switch member 171. The top contact and right-hand contact of the switch 166 are connected with the line L. The bottom contact is connected to one side of the right-hand torch-tilting solenoids 33 and 45. The left-hand contact of the switch 166 is connected with the left-

hand solenoids 33 and 45. The sides of the solenoids away from their connections with the switch 166 are grounded, so that with the rotary member 171 of the switch 166 in the position shown in Fig. 4^b there is a closed circuit through the left-hand solenoids 33 and 45. A quarter-turn of the rotary member 171 opens the circuit through these left-hand solenoids 33 and 45 and closes a circuit through the right-hand solenoids 33 and 45.

Fig. 5 is a sectional view through one of the solenoid-operated valves that control the gas supply. The solenoid 150 has a plunger 175, the lower end of which serves as a valve. In the construction illustrated, the valve comprises a hard rubber insert 176 held in a groove in the bottom of the plunger. The insert is forced against the lip of a valve port 177 by a spring 178 at the top of the plunger. The valve, therefore, has a bias toward closed position (the combined force of the spring 178 and weight of the plunger) and opens only when the solenoid 150 is energized.

The sequence of operation of the machine will be described briefly.

The rail to be cut is fed in against an appropriate stop and clamped to eliminate any movement while cutting. The lower torch slide 16 (Fig. 1) is moved by rotating the hand wheel 67 manually, and with the clutch 68 disengaged, until the cutting jet orifice of the lower torch 40 is beyond the far edge of the rail flange. The cam member 97 is then moved along the track 92 of the torch slide 16 until this cam member contacts with the roller 91 of the limit switch 99. The cam member is locked in position.

The torch slide 16 is then returned until the torch holder and all parts are clear of the rail and will not be struck by the crop end when it falls. The cam member 94 is moved into contact with the roller 91 of limit switch 94 and locked in position. These adjustments establish the automatic travel of the torch 40 when in operation on the particular size of work-piece, as the rail 38.

The movable frame 10 is shifted vertically by operating the hand wheel 85 until the torch 27 is at a level that puts it in correct cutting relation to the ball of the rail 38. The upper torch slide is moved by hand until the cutting orifice is beyond the near edge of the rail ball. The cam member 94 is shifted along the track 92 until it contacts with the limit switch 87 and is then locked in position. The torch slide 12 is then moved the other way until the cutting orifice of the torch is beyond the far edge of the rail ball. The cam member 97 is moved into contact with roller 91 of limit switch 88 and locked.

The main switch in the switch box 101 is then closed by pushing the top button. This supplies power to the solenoids 33 and 45 that tilt the torches. If the torches do not slant toward the main part of the rail, the main switch may be opened and then closed again, or the motors and limit switches may be made to operate once, to cause the solenoids 33 and 45 to tilt the torches the other way.

The machine is then ready to operate. The gas pressures are set. The lower button of the acetylene control switches (switch box 102) is pushed. This causes fuel gas to be supplied to the lower torch 40. The gas is ignited, and the lower button of the preheating oxygen control switches (switch box 103) is pushed and causes oxygen to be supplied to the preheating flames of torch 40.

The hand wheel 67 is rotated manually to ad-

vance the torch slide 16 until the preheating flames of the torch 40 strike the inside edge of the rail flange. The clutch 68 is engaged and as soon as the metal of the flange becomes hot, the lower cutting oxygen button (switch box 104) is pushed. This button causes cutting oxygen to flow to the torch 40 and starts the motor 48 in a direction to shift the torch slide 16 to the right while the lower cutting torch 40 cuts through the flange and part-way through the web of the rail 38.

When the lower torch 40 has finished its cut, the cam member 97 comes against the roller 91 of limit switch 99 and operates this limit switch to shut off all gas to the torch 40 and reverse the motor 48 so that the torch slide 16 is returned to its starting position. The return stroke is made at high speed without governor control. Operation of the limit switch 99 stops the motor at the end of the return stroke of the torch slide 16.

The motor will coast after the power is cut off but all of the cam members are long enough so that they do not travel beyond the limit switch rollers 91 when there is an over-travel of the torch slide as the result of coasting of the motor.

Upon completion of the bottom cut, the upper acetylene control button (switch box 102) and upper preheating oxygen control button (switch box 103) are operated in sequence, and the upper torch 27 brought into position to heat the far side of the ball of the rail. When the metal is hot the upper cutting oxygen control button (switch box 104) is operated to turn on the cutting oxygen jet and start the motor 47. The motor shifts the torch 27 toward the machine while the torch cuts the ball and the uncut portion of the flange of the rail. When the cam member 94 operates the limit switch 87, the gas flow to the torch 27 is shut off and the motor 47 is reversed to return the torch 27 to its starting position at which it is stopped by the operation of the limit switch 88.

The preferred embodiment of the invention has been described, but changes and modifications can be made and some features of the invention can be used without others. The automatic control feature is applicable to cutting machines of various kinds. Terms of orientation are, of course, relative.

I claim:

1. A rail cutting machine including a frame, two independently movable slides, guides on the frame in which said slides move horizontally and parallel to one another, a torch holder on one slide in position to support a torch over the ball of a rail for cutting through the ball and a portion of the web, and a torch holder on the other slide in position to support a torch under the flange of the rail for cutting through the flange and the remaining portion of the web.

2. In a rail cutting machine as claimed in claim 1, power mechanism operably connected with the slides and constructed and arranged to move the slides in such a way that the torch holders move successively, transversely across the rail.

3. In a rail cutting machine as claimed in claim 1 with power mechanism for moving said slides in the guides, said mechanism including a governer-controlled motor means, and motion-transmitting connections between the motor means and each of said slides.

4. In a rail cutting machine, a frame on which are two parallel horizontal guideways, one at a

higher level than the other, a slide independently movable in each of the guideways, a torch holder on the upper one of the slides for holding a cutting torch above a rail, and a torch holder on the other one of said slides for holding a cutting torch under the rail, and power operating mechanism for moving the slides in the guideways to traverse a rail with torches in said holders, said mechanism including one or more electric motors.

5. A rail cutting machine comprising a frame on which are two parallel guides, torch-supporting slides that move in the guides to shift torches supported by the slides across the rail to be cut, mechanism for causing each of the slides to move in its guide, said mechanism including a manually-actuated motion-transmitting means for moving each slide, and a clutch for connecting said mechanism with power driving means.

6. In a cutting machine, a frame in which are two parallel guideways, a slide in each of said guideways, a torch holder supported by the end portion of each slide for holding cutting torches above and below a work-piece, and a cross slide in the connection of one torch holder to its supporting slide for moving that torch holder at right angles to the direction of movement of the slides to bring the torches into position to operate on the work-piece at the same section lengthwise of the work-piece.

7. In a rail cutting machine, a support, a torch holder carried by the support, mechanism for moving the support to traverse the torch holder and a torch carried by the holder across a rail to be cut, and means controlling the position of the torch so as to obtain a parallel or concave side for the kerf on the side of the kerf which is the new end face of the rail after a battered end is cut off, said means including adjustable abutments carried by said support and on opposite sides of a median line, and means for causing the torch holder position to be determined first by the abutment on one side and then by the abutment on the other side.

8. In a machine for cropping off the worn ends of rails by means of an oxygen cutting torch which is moved across the rail to make a transverse cut, a torch support movable to shift the torch across the rail, a torch holder on said support, and means for compensating for variation in the width of the kerf at different depths of the cut, the compensating means including two abutments carried by the support for positioning the torch on a predetermined slope transversely of the direction of the cut, each abutment being set for the cut at an opposite end of the rail.

9. A machine for cutting worn ends from rails, including in combination a torch holder and apparatus for moving the torch holder across a rail so that a torch carried by the holder makes a transverse cut through the rail, and means associated with the torch holder for sloping the torch transversely of the direction of the cut to control the plane of the wall of the kerf, said means including automatic apparatus for shifting the torch position between successive cuts where the worn end is alternately on the right and left sides of the kerf.

10. A machine for cutting worn ends from rails, including in combination a torch holder and apparatus for moving the torch holder across a rail so that a torch carried by the holder makes a transverse cut through the rail, power-operated means for causing said apparatus to move the torch across the rail, a limit device associated with the torch holder for determining a slope

of the torch transversely of its direction of movement when making a cut with the worn rail end on the left of the kerf, another limit device for determining transverse slope of the torch when cutting at the other end of the rail where the worn rail end is on the right of the kerf, and means actuated by the starting of said power-operated means to make said limit devices alternately effective.

10. 11. A rail cutting machine including apparatus for supporting two torches on opposite sides of a rail to be cut and moving the torches transversely of the rail, said apparatus including torch holders positioned in such relation to one another 15 that the torches slope in opposite directions to a common plane and produce a cut that has a plane or slightly concave face on one side of the kerf, which side comprises the new end of the rail after a worn end has been cut off.

12. A rail cutting machine as claimed in claim 11 with means for reversing the angular relation of the torches when the cut is to be made at the opposite end of the rail.

13. A rail cutting machine as claimed in claim 11 with electric motor means for causing the torches to move transversely of the rail, and solenoids connected with the motor circuit for shifting the torches to reverse the angular relation of the torches when the cut is to be made at the opposite end of the rail.

14. A rail cutting machine including in combination a fixed frame, two other frames supported by the fixed frame and at least one of which is vertically movable on the fixed frame, a torch support carried by each of said other frames, the torch supports being movable with respect to said other frames and being movable horizontally and parallel to each other, torch holders on the torch supports in positions to hold torches in working relation with opposite sides of the same piece of work, and adjusting means operable to shift at least one of said other frames on the fixed frame and thereby change the spacing of the torches.

15. A cutting machine including a fixed support, two frames on the support, at least one of which is movable on the support toward and from the other, a torch-supporting arm carried by each of the frames and movable with respect to said frames in a direction transverse of the direction of relative movement of the frames with respect to each other, and a torch holder on each of the arms.

16. In a cutting machine, a fixed support, two frames on the support, at least one of which is vertically movable on the fixed support as a guide, a horizontally slid able arm in each of said frames, and a torch holder on each arm, the torch holders being in positions to hold torches above and below a work-piece at the same region lengthwise of the work-piece so that each torch cuts part-way through the work-piece and the cuts meet to completely sever said work-piece.

17. A torch cutting machine comprising a torch holder, a support for the torch holder movable to and fro through a predetermined stroke, mechanism operable in two directions for moving said support during both its forward and reverse travel, and automatic control means operable when the torch holder support reaches one end of said stroke for reversing the direction of movement of the mechanism that moves said support.

18. A cutting machine including a torch-supporting arm, an electric motor, motion-transmit-

ting connections between the motor and said arm for shifting the arm to traverse a torch across a work-piece, a reversing switch for controlling the direction of rotation of the motor, an abutment movable with the torch-supporting arm, and means in the path of said abutment for operating the reversing switch to reverse the direction of rotation of the rotor when the torch-supporting arm reaches a given limit of movement.

19. A cutting machine including in combination a torch support movable back and forth to traverse a torch across a work-piece, abutment means movable with said support, a limit-switch actuator at each end of the stroke of the abutment means, a motor-reversing switch operated into motor-reversing position by the actuator at one end of the stroke, and a power cut-off switch operated by the actuator at the other end of the stroke.

20. In a cutting machine, a torch-supporting arm movable to traverse a torch over and back across a work-piece, power mechanism for moving said arm including an electric motor, a governor for controlling the motor speed during movement of the arm in one direction, which is the direction of the cutting stroke of the torch, and automatic switch means operated by movement of the torch-supporting arm beyond a given limit, said switch means including a reversing switch that changes the direction of rotation of the motor and a circuit that by-passes the governor so that the motor operates at high speed and without governor control when moving the torch-supporting arm in the other direction.

21. A cutting machine including two torch-supporting arms independently movable through a predetermined stroke for traversing separate torches across opposite sides of a rail or other work-piece to be cut, separate motors for moving the respective arms, switch-operating means responsive to the movement of each of said torch-supporting arms, and a reversing switch for each of the motors actuated by the switch-operating means that is responsive to the movement of the arm driven by that motor, the switch-operating means for one of the reversing switches being responsive to movement of its torch-supporting arm in a different direction from the other switch-operating means.

22. In a cutting machine in which a torch-supporting arm moves a torch across a work-piece and then returns the torch to starting position, the combination with said supporting arm of a motor, means actuated by movement of the supporting arm for automatically reversing the motor, a device for controlling the supply of cutting oxygen to the torch, and control means actuated by said device for starting the motor.

23. A cutting machine including in combination a torch support movable to and fro through a given stroke to traverse a torch across a work-piece, means including an electric motor for

6 moving said support, a governor for controlling the motor speed, a device for controlling the supply of cutting oxygen to the torch, control means actuated by said device for starting the motor with the governor in the motor circuit, a switch for reversing the motor and cutting the governor out of the circuit, and means actuated by movement of the supporting arm for operating the reversing switch.

10 24. A torch cutting machine with valve means for controlling the supply of gas to the torch, an attendant-actuated control device operably connected with the valve means so that actuation of the control device causes substantially simultaneous operation of the valve means into open position, means for holding said valve means open after the attendant releases said control means, mechanism for moving a torch across a work-piece, and automatic means responsive to the travel of the torch for causing the valve means to close.

15 25. Torch cutting apparatus including a valve for controlling the flow of gas to a torch, said valve having a bias toward closed position, electromagnetic means for opening the valve and holding it open, a switch for supplying current to said electromagnetic means, a relay for closing the switch, an attendant-operated switch for closing the relay circuit, a stick circuit for keeping the relay energized after the attendant-operated switch returns to open position, means for moving the torch along a course, and automatic means responsive to the travel of the torch for opening said stick circuit so that the electromagnetic means permits the valve to close.

20 26. Torch cutting apparatus including a number of valves for controlling the supply of fuel gas, preheating oxygen, and cutting oxygen, respectively, to a torch, movable supporting means for traversing a torch across a work-piece, a spring urging each of said valves toward closed position, a separate solenoid for opening each of said valves and for holding it in open position, a relay-operated switch controlling the energizing of each solenoid, a stick circuit for holding the relay-operated switch closed so as to maintain the power supply to the solenoid and keep the valve open, an attendant-operated momentary contact switch for initially closing the circuit that causes the relay-operated switch to close, similar attendant-operated, momentary contact switches for all of the gas supply valves, mechanism for operating said movable supporting means including an electric motor, a reversing switch for the motor, and limit switch means responsive to the travel of the torch supporting and traversing means for opening the stick circuits so that the gas supply valves close, and for operating said reversing switch to change the direction of rotation of the motor.
